UNITED STATES PATENT OFFICE.

GEORGE W. DAVIS, OF CHICAGO, ILLINOIS.

DESIGN FOR A GAS-FIXTURE.

SPECIFICATION forming part of Design No. 25,212, dated March 3, 1896.

Application filed January 19, 1895. Serial No. 535,558. Term of patent 7 years.

To all whom it may concern:

Be it known that I, GEORGE W. DAVIS, a citizen of the United States, and a resident of Chicago, in the county of Cook and State of Illinois, have invented and produced a new and original Design for Gas-Fixtures, of which the following is a specification, reference being had to the accompanying drawing, forming a part hereof.

10 This design relates to gas-fixtures for supporting gas-burners, lamp-burners, and the like, and has for its object to provide a novel and ornamental gas-fixture which presents to the eye a distinguishing and characteristic 15 appearance.

The leading feature of the design consists of a ring having depending therefrom a U-shaped frame, the side arms of such frame uniting with the under side of the ring at diametrically-opposite points.

20 The design is illustrated in the accompany-

ing drawing, in which the figure is a perspective view of a gas-fixture embodying my invention.

In the drawing, A indicates a ring and B B 25 the side arms of a U-shaped frame uniting with the ring at diametrically-opposite points. The ring A is flat or band-shaped, and the arms of a U-shaped frame are round in form, the side arms B being curved or bent inwardly at their lower ends and united with a cube C, upon which the burner is directly supported between the side arms, the location of the burner being shown in dotted lines in the drawing for the purpose of illustration. 30 35

What I claim is—

The design for a gas-fixture as shown and described.

GEORGE W. DAVIS.
